(57) **CLAIM**

The ornamental design for, a child-protecting vest to be used in the vehicle, as shown and described.

DESCRIPTION

FIG. 1 is a front view of a child-protecting vest to be used in the vehicle according to my new design;

FIG. 2 is a top plan view thereof;

FIG. 3 is a right side elevation view thereof;

FIG. 4 is a left side elevation view thereof;

FIG. 5 is a rear elevation view thereof;

FIG. 6 is a bottom plan view thereof; and,

FIG. 7 is a rear perspective view shown in condition of use with vehicle seat belts thereof.

The broken line showing of vehicle seat belts in FIG. 7 is for illustrative purposes only and forms no part of the claimed design. The broken lines shown on the child-protection vest to be used in the vehicle are understood to represent stitching.
